B. F. CORNELIUS,
RAILWAY CROSS TIE,
APPLICATION FILED FEB. 16, 1914.

1,097,082.

Patented May 19, 1914

Fig. 1

UNITED STATES PATENT OFFICE.

BENJAMAN F. CORNELIUS, OF LINDSAY, OKLAHOMA.

RAILWAY CROSS-TIE.

1,097,082.

Specification of Letters Patent. Patented May 19, 1914.

Application filed February 16, 1914. Serial No. 819,039.

To all whom it may concern:

Be it known that I, BENJAMAN F. CORNELIUS, a citizen of the United States, residing at Lindsay, in the county of Garvin 5 and State of Oklahoma, have invented certain new and useful Improvements in Railway Cross-Ties, of which the following is a specification, reference being had to the accompanying drawings.

This invention relates to new and useful improvements in railway cross ties and more particularly to that class known as composition ties, the main object of the invention being to provide a railway cross tie constructed of concrete and substantially reinforced so that the same will provide a cross tie which will withstand the weather and the general wear and tear and, at the same time, will securely retain the rails against lateral movement.

Another object of the invention is the provision of a railway cross tie which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claims.

In the accompanying drawing forming a part of this application, Figure 1 is a side elevation of a railway tie constructed in accordance with my invention, parts thereof being broken away and illustrated in cross section. Fig. 2 is a top plan view thereof. Fig. 3 is a bottom plan view; and Fig. 4

40 is an end elevation.

In the construction of my improved cross tie, I prefer to form the same substantially triangular in cross section, as clearly indicated in Fig. 4 and form the same of three 45 sections which are generally indicated by the numerals 1, 2 and 3, the sections 1 and 3 forming the end sections, while the section 2 forms the central section, said end sections being separated from the central section by 50 means of the transversely extending division blocks 4.

The tie sections are provided, adjacent their bottom portions with longitudinal openings in which are arranged the pipes 5 55 which not only serve to reinforce the sections, but provide casings for the longitudi-

nally extending binding rod 6, said rod extending throughout the length of the entire sections and through the blocks 4, nuts 7 being threaded upon each end thereof to securely retain the rod in place. The bottom of the tie is provided upon each end section with the recesses 8 which, when the ties are placed in position, are adapted to receive the ballast, in order to limit the longitudinal movement of the ties upon the road-bed. 60

The tops of the sections of the tie are covered by means of a plate 9, the ends of which are engaged beneath the bottom of the end sections, as shown at 10, thence extended 70 upwardly on a vertical plane, as shown at 11 and thence bent inwardly upon the inclined portion 12 and from there, extend longitudinally across the top of the tie. The top portion of the tie is provided with offsets 13 which are adapted to receive the bases of the rails 14 which are securely held in position by the removable plates 15, said plates being securely bolted to the ties by means of the bolts 16, the ends of said bolts 80 being arranged within the recesses 8 and thence extended upwardly through the end sections and having nuts 17 threaded thereon to retain the same in position. 75

The plate 9 is provided within its intermediate portion with a plurality of longitudinally extending slots 18 which, when the plate is placed in position, will receive a portion of the material of which the tie is constructed, so as to prevent lateral movement of the plate upon the top of the tie. 85 It is understood that the plate is arranged in position upon the tie after the same is formed and before the concrete or other composition has become hardened. In placing the rails 14 in position, it is preferred to have a block of asbestos or any other similar cushioned material which is generally indicated by the numeral 19 placed within the offset portions 13 and upon which 90 the base of each of the rails is adapted to rest. The portion of the plate 9 which extends along the longitudinal top of the tie is retained in place by means of the bolts 20 extending vertically through the tie body. 100 95

From the above description taken in connection with the accompanying drawing, it will be readily apparent that I have provided a simple and durable composition tie which will replace the wooden tie now in 110 general use and which will securely retain the rails when positioned upon said

ties, against any spreading movement. The device as herein shown and described, is extremely simple in construction and can be manufactured at a comparatively low cost.

While I have shown and described the preferred form of my invention, it is obvious that various changes in the details of construction and in the proportions may be resorted to for successfully carrying my invention into practice, without sacrificing any of the novel features or departing from the scope of the appended claims.

It will be noted that by providing my improved composite tie with the binding plate 9 and by extending the rod 9 longitudinally through the tie, a certain amount of elasticity is communicated to the tie.

Having thus described this invention, what I claim is:

1. A railway cross tie including a sectional body formed substantially triangular in shape, cushioning blocks interposed between the tie sections, a binding plate ex-

tending longitudinally across the top of the tie having its ends engaged beneath the ends of the same, and means for retaining said sections in their relative positions.

2. A railway cross tie including a composite formed in three sections, cushioning blocks interposed between said sections, recesses formed in the upper faces of the end sections, a binding plate extending longitudinally across the top of the tie and provided with elongated slots, offset portions formed in the top of the plate adapted to be disposed within said recesses, the ends of said plate extending down over the ends of the tie, and a longitudinal bolt extending through the ends of the plate and the tie sections to retain the same in their effective positions.

In testimony whereof I hereunto affix my signature in the presence of two witnesses.

BENJAMIN F. CORNELIUS.

Witnesses:

CHAS. L. GRIMES,
S. H. WAREN.
